H. A. Coppess by
Browne & Beale Attest.

United States Patent Office.

HIRAM A. COPPESS, OF GREENVILLE, OHIO.

Letters Patent No. 65,546, dated June 11, 1867.

IMPROVED MACHINE FOR DRAINING SUGAR.

The Schedule referred to in these Letters Patent and making part of the same.

TO ALL WHOM IT MAY CONCERN:

Be it known that I, HIRAM A. COPPESS, of Greenville, in the county of Darke, and State of Ohio, have invented a new and improved Sorghum Sugar Separator; and I do hereby declare that the following is a full and exact description thereof, reference being had to the accompanying drawings, and to the letters of reference marked thereon. In the drawings—

Figure 1 represents a perspective view of my invention; and

Figure 2 represents a sectional view of the cone and strainer.

This invention is one of the class known in sugar-making as "separators," having for its object the separation of the liquid from the solid residuum, after the evaporation of cane juice. This object is accomplished by my invention in the usual manner, *i. e.*, by means of a rotating strainer, which exerts a centripetal force upon the solid portion of the residuum, but not upon the liquid, so that the latter is thrown off by its centrifugal force.

While, however, my invention resembles others of its class in its general features, it differs from any of them that I have seen or heard of, in the form of the rotating strainer, which is that of the frustum of a cone, and in other particulars hereinafter described.

To enable others skilled in the art to make and use my invention, I will proceed to describe its construction and operation.

D represents the framework of the machine, which should be of strength sufficient to support the hollow cylinder C of sheet metal which encloses the rotating strainer, and also to support the vertical shaft S, which passes up within the said cylinder and sustains the rotating strainer. A represents the strainer, which consists in this instance of perforated sheet metal lined with wire gauze. Within this strainer, rigidly attached to its base, and concentric with its periphery, is a cone, B, of any suitable material, of a height nearly equal to that of the strainer, through the apex of which passes the vertical shaft S, before spoken of as sustaining the strainer. This cone is provided with a number of radial ribs c extending from points near its apex to its base. The strainer, with its cone, having been set in rotation, the stream of molasses to be operated upon is directed against the cone, and the office of the radial ribs is to knock the molasses in pieces, when thick, and throw it in masses against the gauze lining of the strainer, whereby its constituent parts are more effectually separated. The strainer is of the form of the frustum of a cone, in order both to counteract the tendency imparted to the molasses by its centrifugal force to rise and overflow the upper edge of the strainer, and to reflect it downward when thrown in masses against the strainer from the conical distributor. This is a consideration of considerable importance, as if the strainer were perpendicular or inclined outward, much of its contents would be liable to be thrown out in the two ways mentioned. H and H' are pulleys on the vertical shaft S, of which H is loose and H' fast, through the operation of a feather and groove or other suitable contrivance. A belt is to connect the upper pulley with gearing operated by a steam engine, and thus communicate the desired rotary motion to the strainer. When it is desired to stop the strainer without stopping the engine, this object is effected by simply shifting the belt upon the loose pulley.

The adaptation of this invention to steam or other power, not human, is one of its greatest advantages, as it is killing business to the operator to run a separator by hand.

The enclosing cylinder C is provided at its base with a flange projecting inward, and the flange at its inner edge is provided with a rim projecting upward, so that between the rim and the cylinder is a channel in which the molasses thrown against the cylinder from the strainer collects, and whence it may be drawn off at pleasure through the orifice a.

What I claim as new, and desire to secure by Letters Patent, is—

1. The rotating strainer of the form of the frustum of a cone, as and for the purpose described.
2. The combination of the conical distributor with the radial ribs, substantially as set forth.
3. The rotating strainer A, in combination with the conical distributor B, the vertical shaft S, the fast pulley H', and the loose pulley H, in the manner explained.

H. A. COPPESS. [L. S.]
